UNITED STATES PATENT OFFICE.

GEORGE W. FAIRBANK, OF WAYLAND, MASSACHUSETTS.

SKIVING-MACHINE.

No. 869,889.

Specification of Letters Patent.

Patented Nov. 5, 1907.

Application filed August 20, 1904. Serial No. 221,471.

To all whom it may concern:

Be it known that I, GEORGE W. FAIRBANK, a citizen of the United States, residing at Wayland, in the county of Middlesex and State of Massachusetts, have 5 invented certain new and useful Improvements in Skiving-Machines, of which the following is a specification, reference being had to the accompanying drawings.

My invention relates to mechanism for skiving or 10 beveling strips of leather at the edges thereof in order that the leather may be folded or sewed to other pieces at this point. My invention has particular reference, however, to that type of skiving machine known as the Amazeen, or machine of similar character, which 15 comprises or has a horizontal rotary disk knife co-acting with the face of a feed roll, adapted to support the leather during the cutting, and to feed the same against the knife edge. The position of the leather is defined by means of a gage, and the leather is held against the 20 roll and guide to the knife by means of a presser arm projecting across the face of the roll just in front of the knife edge and by means also of a disk which partially crosses the face of the roll and has a rotary movement, assisting the roll in the feeding of the leather to the 25 knife and also serving to keep the leather pressed against the gage whereby the alinement of the leather strip is maintained during the cutting operation. The face of the roll is ordinarily offset or of two diameters separated by an abrupt shoulder, the rotary disk co-operating with the smaller diameter and the presser arm 30 extending over both, whereby the strip is bent sharply at the shoulder of the roll and only the edge or portion thereof lying on the larger diameter thereof may receive the cutting contact of the knife to be cut there-by. The position that the edge of the leather assumes with regard to the knife by virtue of this odd structure of the roll is such that the strip receives a deep, concave cut, or in other words, becomes gouged out when 35 it should receive a beveled or inclined cut. Practical usage has demonstrated that an edge cut in the way first mentioned is very objectionable for certain kinds of work, the edge being extremely liable to be broken or torn away.

It is accordingly one object of my invention to 40 modify the feeding mechanism of the skiving machine in a way to insure such a presentation of the leather to the cutting edge that upon being cut the flange of the strip has a straight beveled edge, or in other words, is of a long taper in cross section, whereby its increasing 45 strength precludes the possibility of its being torn or broken in ordinary usage. I accomplish this object by eliminating the abrupt shoulder on the face of the roll and substitute therefor a curved surface presenting a rounding edge.

50 In order to properly feed and guide the leather strip to the knife the gage and presser arm, especially at the

point of the gage, should be as close to the knife edge as possible for if the knife is separated too far from the presser and gage, then by reason of the space left the knife may tend to buckle the leather and consequently injure it. This space is often left when the gage is 60 adjusted.

It is accordingly another object of my invention to improve the skiving machine by preventing the buckling or crumpling of the leather at any point between the presser arm and gage and the knife edge. This object I accomplish by providing a curved presser arm which is fixed to the gage so that both may be adjustable together and then providing means by which the gage and curved presser arm may be adjusted 70 around the rounding surface of the knife.

It has already been stated that the feeding and support of the leather during the cutting is by means of a rotary feed roll, to the face of which the disk knife is substantially tangential. This roll, of course, does 75 not provide a flat bearing surface for the strip, but recedes rapidly from the under face of the cutting knife, only supporting the strip against the same at the cutting edge. This construction permits of the leather being seized directly behind the knife for the purpose 80 of adjusting the position of the leather strip in the machine or for drawing the leather taut beyond the cutting edge. The knife being circular, however, renders the operator extremely liable to serious cuts in such manipulation of the strip unless he observes great care. 85

It is accordingly a still further object of my invention to improve the skiving machine by providing means whereby the operator may adjust the leather or draw it from the feeding mechanism without liability to personal injury from the cutter. This feature of the 90 invention consists of a flat guard plate mounted on the machine in the manner hereinafter fully explained.

Figure 1 is a side elevation of the mechanism involving my invention. Fig. 2 is a top plan of the mechanism shown in Fig. 1. Fig. 3 is a cross section on the 95 line 3-3 of Fig. 2. Fig. 4 is a cross section on the line 4-4 of Fig. 1.

Referring to the various figures, the standard 1 of the machine is shown as provided with journals 2, 3 and 4, in which are rotatably mounted shafts 5, 6 and 7, respectively. The shaft 5 carries the skiving knife 8; the shaft 6 the roll 9 for supporting the leather and feeding it against the knife 8; while the shaft 7 carries the disk 10 for holding the leather against the roll 9, and assisting in feeding it properly to the knife. Mounted 100 on the portion 11 of the standard in the manner herein-after explained is the gage arm 18 supporting the gage 13 which co-acts with the roll 9 and disk 10 to guide and maintain the leather strip in proper alinement. 105

To provide for an adjustment or variation of the 110 angular position of the knife, the journals 2 are pivotally mounted on the standard as at 14. The elevation

of the knife may be varied by means of the screw 15 (Fig. 4) engaging the lug 16. This lug is provided with arms 161 to slide in ways on the journal blocks 2 and is engaged by collars 17 fast on the shaft 5. The shaft 7 is yieldingly mounted to have a vertical as well as a rotating movement in journals 4, but is pressed down against the face of the leather by a spring, not shown.

The gage arm 18 terminates, as may be noted, in a flat plate 19 which connects with the portion 11 of the standard. Mounted upon the gage arm 18 and plate 19 is a flat spring 22 carrying beyond the gage the presser arm 21. The spring 22 is secured to the plate 19 by a screw 23. The spring 22 besides being attached to the plate 23 is provided with an adjusting screw 24 which engages the gage arm 18. The tendency of the spring is to lie against the arm 18 and plate 19 and by turning the screw 24 it may be raised at an angle to said arm and plate by which means the position of the presser arm 21 may be vertically changed. It is therefore to be noted that except for the provision made for obtaining a vertical adjustment of the presser arm it together with its supporting spring is fixed to the gage arm and connecting plate so that the position of the gage and presser arm may be obtained by the same adjustment. It is also to be noted that the presser arm 21 extending beyond the gage 13 is made to describe a curve around the edge of the knife, in order that it may lie snugly against the edge of the same and leave no space in which the leather may buckle between the parts. In order that the proper position of the presser arm and gage with respect to the knife may be maintained whatever the adjusted position of the gage may be, provision is made by which they may be angularly and longitudinally adjusted together. Such provision consists of slots 25 and 25' and a locking screw 26. The slot 25 it is to be noted is made in the plate 19 and the slot 25' is made in the portion 11 of the standard. The slots are angularly arranged in such manner that by proper manipulation the gage and presser arm may be made to follow the curve of the knife edge and occupy a position snugly adjacent to the same without sufficient intervening space to give the leather a chance to buckle whatever the position of the gage may be. Then by means of the locking screw 26 the parts may be held fixed in such position.

Fixedly mounted in the lug 16 is the arm 27 carrying a bearing block or journal 28. Mounted to turn and reciprocate in the block 28 is the shaft 29 carrying a guard plate 30. Fast to the shaft 29 are the collars 31 and 32, and between the collar 31 and the block 28 is the coil spring 33, tending to normally force the shaft upward and the collar 32 into contact with the block 28. The tension of the spring 33 may be regulated by adjusting the position of the collar 31 by means of the set screw 38. The block 28 is grooved as at 34 (Fig. 1), and the collar 32 is provided with a lock pin 35 adapted to register with the groove 34 to normally prevent the collar 32 and shaft from turning. Upon pressing the shaft downward, however, against the spring 33 until the lock pin 35 is clear of the groove 34 the shaft and guard 30 may be swung into the position shown in the dotted lines (Fig. 2), whereupon the knife 8 may be removed or sharpened. It will be noted that the guard 30 extends slightly beyond the edge of the knife, as

shown at 36 (Fig. 2), and that it lies just below and very close to the lower face of the knife, and that its inside edge is beveled at 36'. The relative elevation of the guard and knife may be adjusted by adjusting the position of the collar 32 on the shaft 29. This is easily accomplished by virtue of the set screw 37. Since the arm 27 carrying the guard plate is attached to the lug 16, the relative position of the guard and the knife is not affected by the mere angular or longitudinal adjustment of the latter as heretofore described. Of course this particular mounting of the guard is not essential, and in other instances an adjustment of the guard to correspond with the adjustment of the knife may be necessary.

The roll 9 is shown as having two faces, 40 and 41, 80 the one an offset continued into the other by a curved incline 42. The first of these faces, or offset 40, is adapted to pass under the knife edge, and the relative position of the knife edge with regard thereto is adjusted to accord to the thickness of the leather to be cut, and to the scarf or bevel it is desired to give the same. The gage 13 sets closely over this section of the roll, its outer or guiding face being shown as just about at the edge 43 of the incline 42, thereby delimiting the inmost position of the edge of the leather over the roll. The portion of the gage 13 on the face 40 may, however, be adjusted as by the means heretofore described. The yieldingly mounted disk feed 10, overlies the face 41 of the roll and presses the leather against the same. The presser arm 21 extends beyond the gage 13, serving to hold the leather down and, by extending over the disk 10, prevents the latter from being forced by the leather into contact with the knife.

The strip of leather being placed under the disk 10, and its corner against the gage 13, the rotation of the roll carries it toward the knife, while the gage 13 causes its inside edge to remain in the plane of the edge 43 of the incline 42. The leather being forced between the roll face 40 and incline 42, on the one hand, and the disk 10 and presser arm 21 on the other, takes the position and shape shown in Fig. 3. This causes its edge to be presented at such an angle to the knife edge that upon contact with the latter the cut takes the form of a long bevel. The strip continuing under the knife, passes under the guard plate 30, the beveled edge 36' thereof causing the leather to turn downward on any contact therewith, and, continuing further, may be seized by the operator to be drawn out.

Whereas I have disclosed a specific embodiment of my invention, it is apparent that certain modifications may be made therein without departing from the spirit of the invention.

What I claim as my invention is:

1. In a skiving machine, a rotatable disk knife, a shaft by which said knife is carried, said shaft being mounted to have angular and longitudinal adjustment, a semi-circular guard plate entirely below and extending slightly beyond the rear edge of the knife, and mounted to maintain its position relative to the knife upon adjustment of the latter.

2. In a skiving machine, a leather supporting and feeding roll comprising a cylindrical surface, a conical surface having a curved continuation joining with said cylindrical surface as described.

3. In a skiving machine, a rotatable disk knife, a leather supporting and feeding roll co-acting with the said knife to feed the leather thereto comprising a cylindrical feeding surface, and a conical surface, said cylindrical and conical

surfaces being joined by a curved surface consisting of a continuation of the conical surface as described.

4. In a skiving machine, a rotatable disk knife, a guard located beneath said knife, said guard being pivotally mounted upon its support to permit of its being swung from under the knife.

5. In a skiving machine, a rotatable disk knife, a guard located beneath said knife, said guard being pivotally mounted upon its support to permit of its being swung from under the knife, and a spring lock for normally preventing movement of said guard on its pivot.

6. In a skiving machine, a rotatable disk knife, a guard located beneath said knife, said guard being pivotally mounted upon its support to permit of its being swung from under the knife, means for maintaining said guard normally locked against movement on its pivot, and means for releasing said lock.

7. In a skiving machine, a rotatable disk knife, a guard located beneath said knife, a pivotal rod or shaft on which said guard is mounted to be swung from under the knife, said rod having a longitudinal movement in its bearings and having fast thereon a collar, a stationary collar or lug with which the collar on the shaft is adapted to engage to prevent rotation of the shaft, and a spring to normally hold said collars in engagement, substantially as described.

8. In a skiving machine, in combination with a frame or standard, a rotary knife, a gage and its support, a presser arm connecting therewith, the same being curved to conform to the periphery of the knife, said gage support having an adjusting slot whereby it may be adjusted longitudinally, the said standard having a slot substantially right angles to the slot in said gage when said gage is in place,

and an adjusting screw adapted to pass through both slots, as set forth.

9. In a skiving machine, a rotatable disk-knife, a shaft by which said knife is carried, said shaft being mounted to have angular and longitudinal movement, a semi-circular guard plate or disk just beneath and extending slightly beyond the rear edge of the knife, and mounted to maintain its position relative to the knife upon adjustment of the latter, and means whereby the guard may be adjusted upon the machine to permit free access to the knife edge.

10. In a skiving machine, a rotatable disk knife, a semi-circular guard located beneath said knife, said guard extending beyond the rear edge of said knife and being beveled at its forward end to deflect the material upon contact therewith.

11. In a skiving machine, a rotary knife, a presser arm curved to conform to the periphery of the knife, a gage, and means whereby said gage and curved presser arm may together in proper coördination of position be moved around the edge of said knife and said presser arm maintain a proper position snugly adjacent thereto through the extent of its said curvature.

12. In a skiving machine, a rotatable disk knife and a feed roll co-acting with the edge thereof, said roll having faces of two diameters and between the same said roll presenting an outwardly rounding surface, and means for causing the leather to conform to the outline of said surface, substantially as and for the purposes set forth.

GEORGE W. FAIRBANK.

In presence of—

M. V. FOLEY,
M. E. FLAHERTY.
